NEW YORK.

CIGARETTE CASE.

Application filed September 30, 1926. Serial No. 138,685.

This invention relates to the class of cases, and has especial reference to cigarette cases.

The principal object of the present invention is the production of a case made up of 5 sections which move automatically to an opened relationship to render the contents thereof accessible, and which sections are capable of being moved to a closed relationship; the opening and closing operations being possible of performance by the use of one hand.

Another object of the present invention is the production of a case made up of case forming sections which are releasably held 15 in a closed relationship in a novel manner, and which are released by exerting pressure on a position of one of the sections to be moved to an opened relationship by a means which acts simultaneously on all of the sections.

Another object of the present invention is the provision of a cigarette case of the indicated character which may be made of precious metal, such as gold, with inwardly 25 projecting flanges respectively on opposite side portions of the body sections of the case to give the necessary strength to the body sections, and constituting facing abutments to insure proper closing of the body sections, 30 so that the closure section or cap of the case will fit over the ends of both body sections to hold them together, and a retaining member connected with the inner edges of the flanges of each body section to hold the cigarettes arranged therein in place, each retaining member being located within the 35 plane of its related flanges so that the body sections may close properly.

The nature of the invention and its distinguishing features and advantages will appear when the following specification is read in conjunction with the accompanying drawing, in which:

Figure 1 is a view of a case embodying the 45 present invention; a hand being shown in dot and dash lines illustrating the manner in which the case is opened by the application of pressure with the thumb of the hand on a portion of one of the case sections which 50 releases all of the sections for the opening action.

Figure 2 is a perspective view of the case in its opened condition.

Figure 3 is a sectional view showing the 55 type of hinged connection between sections

of the case, and the means for imparting relative movement of one section with respect to the other.

Figure 4 is a sectional view taken on the line 4—4 of Figure 3.

Referring now more particularly to the drawing, it will be apparent that, in the illustrated embodiment, the case of the present invention includes case forming sections 10, 11 and 12. The said sections may be 60 made either of precious or base metal, or any other suitable material. The sections 10 and 11 are substantially similar in construction, and when brought together form a hollow body or receptacle, and will therefore hereinafter be referred to as body sections. Each 65 of the sections 10 and 11 has a retaining member 13 hingedly connected as at 14 to an inwardly projecting flange 14' on one side portion of the section and adapted to releasably engage a similar inwardly projecting flange 14' on the other side portion of the section at a point directly opposite the hinged connection, as at 15. It is to be noted 70 that when the cigarette case is produced from precious metal, such as gold, which will be comparatively thin, the flanges 14' serve to strengthen the body sections 10 and 11, and constitute facing abutments which insure the proper closing of the body sections 75 10 and 11. Each retaining member 13 is located within the plane of its related flanges 14' so as not to interfere with the proper closing of the body sections 10 and 11. Each 80 section 10 and 11 is adapted to receive a number of cigarettes as shown most clearly in Figure 2. The sections 10 and 11 are connected together at their lower ends by a 85 hinge construction 16. The hinge construction 16 is of a well known type and consists of coacting loops or eyes 17 respectively on the sections 10 and 11 and an element 18 which extends through the eyes 17. The 90 element 18 serves as a means permitting a hinge action, and also has a normal tendency to move the sections 10 and 11 relatively with respect to each other to an opened relationship. Each of the sections 10 and 11 has a neck forming portion 19. When the 95 sections 10 and 11 are brought together the portions 19 combine to produce a neck at the upper open end of the hollow body or receptacle formed by the sections 10 and 11. The section 12 is in the form of an end section or closure, and is adapted to fit over the 100 105 110

neck presented when the sections 10 and 11 are brought together, as shown most clearly in Figure 4. The section 12 is hingedly connected to the body section 10 by a hinge construction 20, similar to the hinge construction 16. The hinge construction 20 consists of loops or eyes 21 respectively on the sections 10 and 12, and an element 22 which extends through the eyes 21. The element 22 permits the end section 12 to hinge on the body section 10, and has a normal tendency to move the section 12 to an opened position. When the end section 12 is closed over the neck formed by the portions 19 on the sections 10 and 11, it serves to hold the sections 10 and 11 against movement away from each other to an opened relationship. This holding action of the end section 12 is supplemented by a holding and releasing means embodied by the body section 11 and the end section 12. In the present instances the said holding and releasing means consists of a projection 23 on the inside of an edge portion of the end section 12, and flexible portion 24 embodied by the body section 11; the said flexible portion 24 having an opening 25 therein, into and out of which the projection 23 moves in the flexing of the portion 24. When the sections 10, 11 and 12 are in the closed relationship, the projection 23 will extend into the opening 25 in the flexible portion 24. By taking hold of the case in one hand, the flexible portion 24 may be pressed inwardly with the thumb of the hand, and as a consequence the projection 23 will be disengaged or released. This will be followed by the action of the element 22, which will cause the end section 12 to move to an opened position from over the neck formed by the portions 19. By separating the thumb and fingers of the hand with respect to each other, the element 18 of the hinge construc-

tion 16 will come into play and move the sections 10 and 11 to an opened relationship as shown in Figure 2. Thus the case may be 45 opened easily and quickly with one hand. By bringing the sections 10 and 11 together from the opened relationship with the fingers and thumb of the hand, the end section 12 may be brought over the neck formed by the 50 fore-finger of the hand to a closed relationship. During the closing of the end section 12, the projection 23 will enter the opening 25 as the portion 24 is flexed inwardly, and will be held in the opening when the flexible 55 portion 24 returns to its normal position.

It is to be understood that the invention is not reconstructed to the precise arrangement of parts shown and described, as details of construction may be modified and 60 rearranged without departing from the spirit of the invention, the scope of which is limited only by the terms of the appended claim.

We claim:

A cigarette case, comprising a pair of body 65 sections, a spring hinge connecting said body sections at one end, a closure, a spring hinge connecting said closure to one of the body sections, said closure adapted to fit over the ends of both body sections, coacting means 70 on the closure and one of said body sections serving to releasably hold the closure and body sections together, inwardly projecting flanges respectively on the side portions of both body sections strengthening the body 75 sections and constituting facing abutments, and a retaining member connected with the inner edges of the flanges of both body sections and located within the plane of said flanges.
